WILLIAM H. WOOD, OF SOUTH EUCLID, AND IRA W. CROUSE, OF CLEVELAND, OHIO

SIGNAL SYSTEM

Application filed December 30, 1929. Serial No. 417,271.

This invention relates to signal systems of the type known as block signals for controlling the operation of railway trains and has for its object the provision of resistance devices automatically operable to compensate for variable conditions produced by the weather; the provision of means for increasing the certainty and reliability of operation of the signals; to reduce the cost of maintenance and supervision; to increase the life of the signal batteries; while further objects and advantages of the invention will become apparent as the description proceeds.

Certain typical illustrative embodiments of our invention are shown in the annexed drawings. Fig. 1 is a diagram illustrating a signal-block with its essential connections as arranged for use with a direct-current track-circuit for steam or alternating-current propulsion; Fig. 2 is a diagram illustrating a signal-block with its essential connections as provided for use with alternating-current track-circuits with steam propulsion. Fig. 3 is a diagram illustrating a signal-block with its essential connections as provided for use with alternating-current track-circuit for roads having direct-current electric propulsion. Fig. 4 is a perspective view of a standard apparatus-box having one form of our invention affixed thereto and shown partly in section. Fig. 5 is a vertical sectional view through the auxiliary casing shown in Fig. 4; Fig. 6 is a reduced top-plan view of the resistance board shown in Fig. 5; Fig. 7 is a perspective view of a preferred type of salt canister; and Fig. 8 illustrates a slight modification of circuits.

Before describing our improvements we desire to explain briefly the essentials of a typical installation to assist in the understanding of the manner in which our improvements are applied thereto and the problems which they are designed to solve. According to the usual contemporary practice the respective rails 1 and 2 of each track

are joined in electrical contact one after the other for a considerable distance, for example one mile, being insulated from the rails beyond by suitable insulating joints 3, 3 and insulated from each other, theoretically, by the wood ties 4 which support the same. Connected to the respective rails adjacent to one end of each block are lead-wires 5 and 6 connected to a suitable source of E. M. F.; and connected to the respective rails at the opposite end of the block are the terminals 8 and 9 of the relay magnet 10. The armature 11 of this relay moves between contacts 12 and 13, the contact 12 being connected to the "white" or clear signal 14 and the contact 13 to the "red" or danger signal 15. These two signals are then joined by a connection 16 to one terminal of the operating battery 17, the opposite terminal of which is connected to the armature 11. We have employed the letters "W" and "R" to indicate the clear and danger signals respectively, which may of course consist either of lights or of movable semaphore arms or of other targets according to the practice of the particular installation. So long as the two rails remain electrically disconnected the armature 11 is supposed to be attracted by the magnet 10 and to make contact at 12 thereby displaying the clear signal; but the presence of any short-circuiting element, such as the wheels and axle of a railway car, demagnetizes the relay 10 and allows the armature to make contact at 13, displaying the danger signal. The same effect follows any other accident to the system such as depletion of the battery, or other current-source failure, or failure of the connections, or any accident to either of the rails; but unfortunately the same result often follows any wetting of the track, as by a shower, especially in case the ties be impregnated with salt or with the refuse from stock-cars. After every shower the leakage from rail to rail along the ties is likely to become so great as to set the block 90

signal at danger unless a sufficient amount of current is supplied to compensate for this leakage; yet on the other hand to maintain this amount of current at all times tends to produce an early depletion of the battery, especially in those blocks where trains are liable to stand still for any reason. Furthermore there are two distinct operating disadvantages of employing an unduly high current, namely: that of so highly magnetizing the relay 10 in dry weather as to prevent it from releasing its armature when the tracks are short-circuited by a train; and second the danger that under poor contact conditions as with a dry rusty track produced by a dewy night, a light conveyance, such as a gasoline motor, might fail to by-pass a sufficiently large part of this large current to release the armature 11. Either of these last contingencies produces a clear signal with an occupied track which is completely inex-
cusable.

This difficulty with the weather often requires the blocks or track-sections to be made much sorter than would otherwise be desirable for operating purposes; and further to compensate for weather conditions, means are customarily provided for adjusting the E. M. F. applied to the track. When the current-source is a battery as shown at 19 in Fig. 1 this means ordinarily comprises a variable resistance 20 connected in series between said battery and the wires 5 and 6 and having an adjustable contact 21, movable ordinarily between a minimum of about 0.2 ohm and a maximum of about 0.9 ohm for a primary battery or between about 1.2 and 5.0 ohms in case of a storage battery. In fair weather it is desirable to have the resistance set at the maximum figure in order to save battery depletion, avoid over-magnetizing the relay and guard against signal failure; but in wet weather, or particularly after a sharp shower, a larger E. M. F. is desirable, which means either that an attendant must vary the resistance to compensate for the leakage between the rails, or that the resistance is set permanently at such a point as will most nearly operate under the varying conditions encountered on that block.

According to our invention we provide an auxiliary element capable of being applied to and used with the existing equipment, and operating automatically to increase the E. M. F. supplied to the track during wet weather and to decrease such E. M. F. in dry weather. Ordinarily the electrical equipment, batteries, resistance, relays, etc. are housed in iron boxes 25 mounted on posts 26 located alongside the track adjacent to the junctions between successive blocks. Each one of these boxes ordinarily contains the E. M. F. producing apparatus for one block, and the signal-controlling apparatus for the next succeeding block, as shown by the out-

lines 25, 25 in Fig. 1. Our apparatus is preferably secured directly to the exterior of this box so that the electrical connections need merely to be introduced through a hole made in the latter for that purpose; and comprises an element for collecting the precipitated moisture, a circuit normally open but closed upon the presence of a predetermined amount of such moisture, and arranged to increase the E. M. F. by a predetermined degree.

An illustrative embodiment of a preferred mechanism is shown in Figs. 4 to 7; the diagrammatic connections being illustrated in Figs. 1, 2, and 3. In this form we provide a sheet-metal casing having side-walls 27 and slanting roof 28, secured to the box 25 by suitable bolts 29. One side of the casing is made movable as by the hinges 30 and padlock 31, while air-circulation is allowed by forming louvers 32. Mounted in inclined position in this casing is a support 33, of some inexpensive non-conducting insoluble substance. A common board is as good as anything so long as it lasts, although for permanence we prefer stone, or porcelain or earthenware. On the top of this are laid a plurality of parallel spaced wires 34 extending from top to bottom without touching each other, alternate wires being connected into two circuits as shown in Fig. 6 with terminals or binding posts 35, 35. Preferably a layer of somewhat porous absorbent material is introduced between the wires and support as shown at 36, which may be of paper or paper-pulp, though for permanence we prefer asbestos or magnesia in case it be employed at all or other mineral substance.

Formed in the roof of the casing is a funnel-shaped depression 37, beneath which is a shelf 38 adapted to deliver liquid falling thereon to the upper end of the support 33, and interposed between this funnel and shelf we have shown a canister 53 charged with a slow-dissolving salt or composition containing salt indicated at 39, said canister having upper and lower perforated heads 40, 40. For purposes of convenience we term these wires 34 the "grid"; and we connect this grid between the two poles of the battery 19 (or other potential-producing device) in circuit with a relay magnet 41. The relay-armature 42 and its contact-point 43 are connected, one to one end of the resistance 20 and the other to an additional contact 44 applied thereto at a proper point.

The operation of the mechanism so far described is as follows: Whenever precipitated moisture passes through the funnel 37 it wets the support 33 and the grid 34 thereon in such manner as to establish an electric connection between the elements of the grid whereupon the armature 42 is attracted, thus reducing the resistance in circuit between the battery 19 and the track so as to increase the current flow and thereby compensate for

the simultaneous wetting of the ties. As soon as precipitation ceases the track begins to dry out and so does the apparatus. The main object of employing any porous substance at 36 is to arrest the drying of the apparatus so that it shall not become non-conducting in advance of the road-bed. Depletion of the battery 19 due to a train standing on the track while the wet-weather conditions exists is prevented by the following circumstance: That inasmuch as the battery 19 serves both the track and the relay 41, the short-circuiting effect on the track automatically demagnetizes the relay 41, and restores the resistance to dry-weather conditions until the short-circuiting element has been removed whereupon the apparatus rests itself if still warranted by the weather. This temporary restoration of the resistance to dry weather conditions is not alone sufficient to cause the reatraction of the relay armature 42 because of the air gap effect which necessitates a larger increase of magnetizing current to attract the armature than decrease to release it. The ratio between these can readily be adjusted by varying the air-gap.

It is well-known that a quick, sharp shower is more troublesome than a long rain since the latter dissipates the soluble conductive salts, generally occurring in the road-bed, while the former produces a conductive solution of the highest concentration. It is hence particularly important that a short, sharp shower shall produce the desired operation of the apparatus; and also that the effect of a long rain be somehow decreased in order to diminish the wasteful solution of the conductive substance with which the apparatus is in some manner charged.

One mode of effecting this is illustrated in Figs. 4 and 5, viz: the roof 28 is provided with an open-topped chimney 45 of rather large diameter surrounding the funnel 37, and pivoted inside this chimney on the horizontal axis 46 is a tipping basin 47. One end of this basin overhangs the funnel 37 and is formed with a small discharge aperture 48 adapted to deliver thereinto, while the opposite end of the basin is provided with a waste aperture 49. The pivot 46 is located comparatively close to the aperture 48, but the unbalanced weight thereby produced is slightly overcome by means of a counter-weight 50 adjacent to the funnel 37.

The basin 47 therefore acts in position and inclination as an auxiliary to the funnel 37, and upon the beginning of any rain, delivers its entire contents into this funnel until the collection of an amount of liquid therein more rapidly than it can be discharged through the aperture 48 causes it to become tilted to the position shown in dotted lines in Fig. 5, whereupon its collected liquid is discharged by overflow and by way of the restricted aperture 49 through the waste-aperture 51 in

the base of the chimney. Meanwhile the moisture of the grid 34 is maintained merely by the rain which falls directly into the funnel 37, the size of which is chosen with this in view.

This tipping-basin is a refinement which may or may not be used, since its only function is to economize the solute. Also the solute can be supplied in other ways. It is often sufficient for a long time if merely the grid-support be impregnated with a slowly dissolving salt; and it is possible to arrange a solute supply through which only a part of the liquid passes. However if one of the slow-dissolving rock-salts or artificial, slow-dissolving, salt-containing composition such as is widely sold for stock-feeding purposes, be employed it is possible to introduce a six months' supply without employing an unduly large amount, and we have found it very convenient to effect this by means of a cylindrical canister having inwardly bowed perforated ends to help distribute the liquid, combined with opposite overlapping removable lids 52—52 for use during transportation or storage.

The arrangements illustrated in Fig. 1 can be employed with steam propulsion or, with small precautions, with alternating current electric propulsion, but not, of course, with direct-current propulsion. In Fig. 2 we have shown our improvements as arranged for use with alternating current track-circuits with steam propulsion. In this case the source of E. M. F. consists of the secondary winding 60 of a suitable transformer producing for example, 10 volts. To vary the current supplied to the track a suitable variable inductance is ordinarily employed here illustrated as comprising a core 61 having windings 62 provided with taps arranged to be connected together in pairs. The effective resistance between different pairs of the taps is generally written and known in the art as "ohms".

To utilize our invention, we connect a grid 34 and an alternating current relay 41^a in series with each other across the terminals of the winding 60; and we provide said relay with a double armature 42^a adapted when not attracted to include in circuit between the winding 60 and the track a comparatively high impedance (e. g. 2.4 "ohms"), and when attracted to contact with the terminals 43^a to introduce into that circuit a smaller impedance (e. g. 1.7 "ohms"). The auxiliary apparatus required is identically the same as before except that the relay must be one that will operate with alternating currents and its armature must contain two separate contacts.

In Fig. 3 we have shown our improvements as applied with an A. C. track circuit with an electrified road employing D. C. propulsion. Inasmuch as the rails are ordinarily

employed for the propulsion-current return it is necessary that the joints be bridged by connections which shall allow the passage of the direct current while preventing that of the alternating current which operates the signals. For this purpose we have shown the choke-coils 65 bridging the insulated joints. In this case the E. M. F. is produced by a transformer having a primary winding 66 and a secondary winding 67, the latter having plural taps 68, 69, 70. Thus far the apparatus is that often employed heretofore, the track-wires 5 and 6 being connected to these taps between which the desired E. M. F. is obtainable according to weather conditions.

To utilize our invention we connect a grid 34 and alternating current relay 41^a in series with each other across the terminals of the secondary winding 67; and we provide said relay with a double armature 42^a, adapted when not attracted to connect the track in circuit with such taps in the secondary winding as shall afford a comparatively low E. M. F., e. g. 10 volts, and adapted when attracted to contact with the terminals 43^a, to connect the track between taps yielding a higher E. M. F. e. g. 12.5 volts. It will be seen that the same auxiliary apparatus is usable here as before.

In Fig. 8 we have shown the relay 41 as connected to a source of E. M. F., 19^a, separate from the source 19 which supplies the track-circuit. This arrangement is perfectly operative and can be employed with the circuits of Figs. 2 and 3 as well as those of Fig. 1. It sacrifices certain advantages of the preferred arrangement but secures certain other advantages, one of which is that it renders the auxiliary apparatus more nearly self-contained and avoids any additional drain upon the main source of E. M. F.

It will be understood by those skilled in the art that our invention can equally well be employed with single track systems, with or without electric propulsion, although we have refrained from illustrating the same due to the essential complication of providing the circuits necessary to a two-way operation over a single track. Among the advantages of our invention are: the fact that the amount of the change of resistance or E. M. F. as a result of its operation is exactly controllable depending upon the setting of the contact 44 or its equivalent; that it constitutes an additional safeguard whose non-operation cannot in any way injure the previously existing apparatus; and that its operation, not being affected by dew or snow or under excessively cold conditions, decreases the danger of permanent magnetization or of failure of signals by poor train-shunt.

The main reason for inclining the grid support is to impede any collection of cinders thereon which would otherwise tend to vary the drying rate. The size of the different

water openings is made as large as feasible to minimize the tendency to become clogged and the top of the chimney is covered with a screen cloth whose mesh is sufficiently small to arrest particles of a size to clog the liquid apertures. When such a canister is employed as is here shown some of the cinders will be arrested thereby but such of the cinders as fall in the grid support are gradually washed away by the liquid. It is for this reason that we preferably employ a grid of straight parallel wires running with the slant of the support. It will be understood of course, that while we have described at length the particular embodiments that we have selected as illustrative of our invention, and have explained many details of refinement to secure the best possible operation, we do not limit ourselves to any of these details except as the same are specifically recited in our several claims, which we desire may be construed broadly, each independently of limitations contained in other claims.

Having thus described our invention what we claim is:

1. The combination with two parallel rails of a railroad-track-section, together with a relay and a source of electro-motive-force, one terminal of said relay and one terminal of said source being connected to one rail and the other terminal of said relay and the other terminal of said source being connected to the other rail; of a second relay and a normally open, circuit-controlling element connected to said source of electro-motive-force in series with each other and in multiple with said track, means operable by precipitated moisture for closing said circuit controlling element, and means operable by the closing of the armature of said relay for increasing the electro-motive-force supplied to the track.

2. The combination with two parallel rails of a railroad-track-section, together with a relay and a source of electro-motive-force, one terminal of said relay and one terminal of said source being connected to one rail and the other terminal of said relay and the other terminal of said source being connected to the other rail; of a relay and a grid connected to said source of electro-motive-force in series with each other and in multiple with said track, said grid comprising a pair of metal elements supported out of electrical contact with each other and exposed to precipitated moisture and means for impregnating such moisture with a conductive solute.

3. The combination with two parallel rails of a railroad-track-section, together with a relay and a source of electro-motive-force, one terminal of said relay and one terminal of said source being connected to one rail and the other terminal of said relay and the other terminal of said source being connected to the other rail; of a second relay and a pair of spaced metallic members connected to said

source of electro-motive-force in series with each other and in multiple with said track and means operable upon the occurrence of a precipitation of atmospheric moisture to produce and maintain electrolytic connection between said members until said moisture shall have evaporated.

4. The combination with two parallel rails of a railroad-track-section, together with a relay and a source of electro-motive-force, one terminal of said relay and one terminal of said source being connected to one rail and the other terminal of said relay and the other terminal of said source being connected to the other rail; the track connections including an element for controlling the electro-motive-force, of a normally open circuit-controlling element connected to said source of electro-motive-force, means operable by precipitated moisture for closing said circuit-controlling element and for maintaining the same closed until the disappearance of such precipitated moisture, and means operative during the time that the circuit is closed through said circuit-controlling element for increasing the electro-motive-force in the track circuit.

5. The combination with two parallel rails of a railroad-track-section, together with a relay and a source of electro-motive-force, one terminal of said relay and one terminal of said source being connected to one rail and the other terminal of said relay and the other terminal of said source being connected to the other rail; of a relay and a normally open circuit-controlling element connected in series with the relay magnet, there being a source of electro-motive-force in series with said circuit-controlling element and said relay magnet; means operable by precipitated moisture for closing said circuit-controlling element, and means operable by the closing of the armature of said relay for increasing the electro-motive-force supplies to the track.

6. The combination with two parallel rails of a railroad-track-section, together with a relay and a source of electro-motive-force, one terminal of said relay and one terminal of said source being connected to one rail and the other terminal of said relay and the other terminal of said source being connected to the other rail; of a second relay having an electro-magnet and an armature; connections between said armature and the track circuit for controlling the electro-motive-force supplied to said track circuits, and connections controlled by precipitated moisture for governing the current supplied to the relay magnet.

7. The combination with two parallel rails of a railroad-track-section, together with a relay and a source of electro-motive-force, one terminal of said relay and one terminal of said source being connected to one rail and the other terminal of said relay and the other terminal of said source being connected

to the other rail; of means for varying the electro-motive-force supplied to the track by said source, a controlling device for said means, and a device operable by precipitated moisture for actuating said controlling device so as to increase the electro-motive-force supplied to the track upon the precipitation of atmospheric moisture.

8. The combination with two parallel rails of a railroad-track-section, together with a relay and a source of electro-motive-force, one terminal of said relay and one terminal of said source being connected to one rail and the other terminal of said relay and the other terminal of said source being connected to the other rail; of means for varying the electro-motive-force supplied to the track by said source, a controlling device for said means, a body having electrically conductive properties substantially comparable to those of the track-road bed under both wet and dry conditions, said body being exposed to precipitated moisture, and means for actuating said controlling device in accordance with the electrically conductive condition exhibited by said body.

9. The combination with two parallel rails of a railroad-track-section, together with a relay and a source of electro-motive-force, one terminal of said relay and one terminal of said source being connected to one rail and the other terminal of said relay and the other terminal of said source being connected to the other rail; of a relay comprising a magnet and an armature, means operated by varying positions of the armature for varying the electro-motive-force supplied to the track by said source, a body having electrically conducting properties substantially comparable to those of the track-road bed under both wet and dry conditions, said body being exposed to precipitated moisture, and spaced metallic conducting members carried by said body and connected in the magnetic circuit of said relay.

10. In a block signal system, an auxiliary weather-controlling device comprising an inclined, porous support and spaced conductive members thereon which are normally insulated from each other but adapted to become electrically united upon the impregnation of said support by impregnated moisture.

11. In a block signal system, an auxiliary weather-controlling device comprising an inclined support, a pair of spaced metal members carried by said support out of electric contact with each other, means for exposing said support to precipitated moisture and means for supplying a soluble salt to such moisture.

12. In a block signal system, an auxiliary weather-controlling device comprising a support, a pair of spaced electrical conductive members carried thereby, said support being of a type adapted to hold a certain amount

of moisture and to maintain the same in contact with said members, means holding said support in a position to be wet by precipitated moisture and to be dried by atmospheric currents, and means for supplying an ionizable solute to the liquid on said support.

13. In a block signal system, an auxiliary weather-controlling device comprising a support, a grid carried thereby and comprising spaced metallic members ordinarily out of electrical circuit with each other and adapted to be contacted by liquid on said support, means for delivering precipitated moisture to said support, means for supplying an ionizable solute to such moisture and means for automatically reducing the amount of moisture delivered to said support as the violation of precipitation increases.

14. In a block signal system, an auxiliary weather-controlling device comprising a support, spaced conductive members carried by said support and adapted to be connected together electrolytically by precipitated moisture, and means for catching precipitated moisture and delivering it to said support and means for automatically reducing the collecting area which delivers to said support as soon as the rate of precipitation reaches a predetermined amount.

15. The combination with the two parallel rails of a railroad-track-section together with a battery and a relay, one terminal of said battery and one terminal of said relay being connected to one rail, and the other terminal of said battery and the other terminal of said relay being connected to the other rail; the connection between said battery and one of said rails being two branched at least in part; unequal electrical resistances in said branches, and means responsive to weather conditions for automatically closing the circuit through one of said branches when the weather is wet and opening said circuit when the same is dry.

16. The combination with the two parallel rails of a railroad-track-section together with a battery and a relay, one terminal of said battery and one terminal of said relay being connected to one rail, and the other terminal of said battery and the other terminal of said relay being connected to the other rail; the connection between said battery and one of said rails comprising two circuits arranged in multiple, one of said circuits containing a manually variable resistance and the other comprising a shunt past a part of said resistance, and means adapted to be actuated by precipitated water to close said shunt circuit.

17. The combination with the two parallel rails of a railroad-track-section together with a battery and a relay, one terminal of said battery and one terminal of said relay being connected to one rail, and the other terminal of said battery and the other terminal of

said relay being connected to the other rail; of a resistance connected in circuit between said battery and one of said rails and means for shunting said resistance comprising a collecting element for precipitated water, a movable element adapted to be displaced by an effect of such collected water, and a circuit closing device operated by such displacement.

In testimony whereof, we hereunto affix our signatures.
